OUTDOOR PEDESTAL ASH TRAY

Conrad A. Yankee, 103 Seaview Ave.,
West Haven, Conn. 06516

Filed Oct. 30, 1972, Ser. No. 302,020

Term of patent 14 years

Int. Cl. D27—03

U.S. Cl. D85—8 J

FIG. 1

FIG. 3

FIG. 1 is a side elevational view of an outdoor pedestal ash tray showing my new design, a portion of which is broken away for convenience of illustration;

FIG. 2 is a top plan view;

FIG. 3 is a bottom plan view.

I claim:

The ornamental design for an outdoor pedestal ash tray, substantially as shown and described.
